US00D816695S

(12) **United States Design Patent** (10) Patent No.: **US D816,695 S**
 (45) Date of Patent: **** May 1, 2018**

(54) **DISPLAY SCREEN WITH GRAPHICAL USER INTERFACE**

(71) Applicant: **TeleTracking Technologies, Inc.**,
 Pittsburgh, PA (US)

(72) Inventor: **Jason A. Spector**, Pittsburgh, PA (US)

(73) Assignee: **TELETRACKING TECHNOLOGIES, INC.**, Pittsburgh,
 PA (US)

(**) Term: **15 Years**

(21) Appl. No.: **29/581,829**

(22) Filed: **Oct. 21, 2016**

(51) LOC (11) Cl. **14-04**

(52) U.S. Cl. **D14/486**
 USPC **D14/486**

(58) **Field of Classification Search**

USPC **D14/485-488**
 CPC **G06F 3/0482; G06F 3/04842; G06F
 2203/04807; G06F 19/3418; G06F
 19/3406; G06F 19/34; H04M 1/2477;
 G06Q 50/22; G06Q 50/24; G06Q 10/10;
 G06Q 10/06; G06T 2207/30004**

(57) **CLAIM**

The ornamental design for a display screen with graphical user interface, as shown and described.

DESCRIPTION

The FIGURE is a front elevation view of a display screen with graphical user interface showing my new design. The broken lines of uneven length show the display screen and form no part of the claimed design. The broken lines of even length illustrate portions of the display screen with graphical user interface that form no part of the claimed design.

1 Claim, 1 Drawing Sheet
